(57) **CLAIM**

The ornamental design for profile for mower, as shown and described.

DESCRIPTION

FIG. 1 is left side perspective view of a profile for mower showing our new design.

FIG. 2 is a front view of the profile for mower.

FIG. 3 is back view of the profile for mower.

FIG. 4 is left side view of the profile for mower.

FIG. 5 is right side view of the profile for mower.

FIG. 6 is top view of the profile for mower.

FIG. 7 is bottom view of the profile for mower.

FIG. 8 is a right side view of the profile for mower shown in environment.

FIG. 9 is a left side perspective view of the profile for mower in a second embodiment.

FIG. 10 is a front view of the profile for mower in a second embodiment.

FIG. 11 is a back view of the profile for mower in a second embodiment.

FIG. 12 is a left side view of the profile for mower in a second embodiment.

FIG. 13 is a right side view of the profile for mower in a second embodiment.

FIG. 14 is a top view of the profile for mower in a second embodiment.

FIG. 15 is a bottom view of the profile for mower in a second embodiment.

FIG. 16 is a left side view of the profile for mower in a second embodiment shown in environment.

FIG. 17 is a right side perspective view of the profile for mower in a third embodiment.

FIG. 18 is a back view of the profile for mower in a third embodiment.

FIG. 19 is a front view of the profile for mower in a third embodiment.

FIG. 20 is a left side view of the profile for mower in a third embodiment.

FIG. 21 is a right side view of the profile for mower in a third embodiment.

FIG. 22 is a top view of the profile for mower in a third embodiment.

FIG. 23 is a bottom view of the profile for mower in a third embodiment; and,

FIG. 24 is a right side view of the profile for mower in a third embodiment shown in environment.

The broken line portions are included to show environmental unclaimed subject matter only and form no part of the claimed design.

1 Claim, 17 Drawing Sheets
